UNITED STATES PATENT OFFICE.

WILLIAM JOHNSTON AND CHARLES RASMUSSEN, OF NEW HAVEN, CONN.

HINGE FOR LANDAU-TOPS.

SPECIFICATION forming part of Letters Patent No. 244,616, dated July 19, 1881.

Application filed June 6, 1881. (No model.)

To all whom it may concern:

Be it known that we, WM. JOHNSTON and CHARLES RASMUSSEN, of New Haven, in the county of New Haven and State of Connecticut, have invented a new Improvement in Hinges for Landau-Tops; and we do hereby declare the following, when taken in connection with the accompanying drawings and the letters of reference marked thereon, to be a full, clear, and exact description of the same, and which said drawings constitute part of this specification, and represent, in—

Figure 1, a perspective view; Fig. 2, a vertical central section; Fig. 3, a transverse section on line xx ; Fig. 4, a vertical central section on a reduced scale, showing the hinge as open.

This invention relates to an improvement in hinges for attaching landau-top fronts to the front pillars. In the usual construction these hinges are made with a knuckle upon the front, necessarily exposed when the top is raised. The object of this invention is to construct a hinge which, when applied and the top closed, is entirely concealed, so that at the hinging-point nothing is seen but the simple joint between the lower or fixed part of the pillar and the upper or swinging part; and in such a hinge this invention consists.

30 A is the plate or cap which sets upon the top of the stationary part of the pillar. This is a plain flat plate, easily set flush in the upper end.

35 B is a plate or flange, turning down at right angles from the plate A, to be sunk into the side of the stationary part of the pillar, the two parts A and B secured by screws into the pillar.

40 Beneath the plate A, and in rear of the flange B, is a pocket, C, opening through the plate A and forming a slot, D, therein.

45 E is a plate corresponding to the plate A, fitted to the lower end of the swinging part of the pillar, constructed with a right-angular flange, F, extending upward onto the face of the swinging part.

On the under side of the plate E is an arm, H, which extends through the slot D into the pocket C of the stationary part of the hinge, 50 and is hung at the rear of the pocket by a

pivot, I, and so that when the upper or swinging part, E F, is turned on the pivot I it swings away from the plate B—that is, from its vertical position, as seen in Fig. 4, the hinging part being something like what are known as “concealed coach-hinges.”

The plates A B of one part and E F of the other, being sunk into the wood of their respective parts of the pillar, are hidden or entirely concealed when in their closed position, 60 and because of their shape—that is, extending on the ends of the pillar and on the sides—make the strongest possible connection between the swinging and stationary parts of the pillar.

65 In some cases springs are applied to aid in raising the tops—that is, as a kind of counterbalance.

To provide these hinges for the attachment of the counterbalancing springs I construct 70 the swinging part E F with an arm, L, extending downward over the face of the part B, but so that in turning the other part that arm will pass freely over the upper end of the part B, as seen in Fig. 4. One end of the spring is 75 attached to the lower end of this arm L and the other to a point below, so that as the top is turned backward the spring is extended, resisting the falling of the top to some extent; then when the top is raised the spring reacts 80 and aids in raising.

The arm for the spring attachment has usually been applied to some other part of the top; but the arrangement and operation of the spring are too well known to require any further description in this specification.

85 It will be understood that the door-pillar is hinged in the usual manner for this class of falling fronts.

We claim—

90 1. The herein-described hinge for landau-tops, consisting of the fixed part composed of top plate, A, and vertical flange B, with the pocket C, opening through the plate A, combined with the second part, composed of the 95 plate E and vertical flange F, with an arm, H, extending from the plate E into and hung within the said pocket, substantially as described.

90 2. The herein-described hinge for landau-

tops, consisting of the fixed part, composed of top plate, A, and vertical flange B, with the pocket C, opening through the plate A, combined with the second part, composed of 5 the plate E and vertical flange F, with an arm, H, extending from the plate E into and hung within the said pocket, and the arm L, extending to or made a part of the swinging part of the hinge, substantially as described.

WILLIAM JOHNSTON.
CHARLES RASMUSSEN.
